DESIGN FOR A GREENHOUSE

Thomas Edward King, Hartsdale, N. Y., assignor to Lord & Burnham Company, Irvington, N. Y., a corporation of New York

Application June 14, 1944, Serial No. 113,995

Term of patent 14 years

(Cl. D13—1)

To all whom it may concern:

Be it known that I, Thomas Edward King, a citizen of the United States and a resident of Hartsdale, in the county of Westchester and State of New York, have invented the new, original, and ornamental Design for Greenhouse, of which the following is a specification, reference being had to the accompanying drawing, forming part thereof, in which—

I claim.

The ornamental design for a greenhouse, as shown.

T. EDWARD KING.
